UNITED STATES PATENT OFFICE.

CHARLES M. JOHNSON, OF MILWAUKEE, WISCONSIN, ASSIGNOR OF ONE-HALF TO CHARLES H. COAKLEY, WILLIAM F. COAKLEY, AND STEPHEN S. CRAMER, OF MILWAUKEE, WISCONSIN.

BOX-FASTENER.

SPECIFICATION forming part of Letters Patent No. 729,595, dated June 2, 1903.

Application filed March 16, 1903. Serial No. 147,898. (No model.)

To all whom it may concern:

Be it known that I, CHARLES M. JOHNSON, a citizen of the United States, and a resident of Milwaukee, in the county of Milwaukee and State of Wisconsin, have invented certain new and useful Improvements in Box-Fasteners; and I do hereby declare that the following is a full, clear, and exact description thereof.

10 Experience has demonstrated that careless, mischievous, or malicious effort exerted on the spring-latch element of a box-fastener made in accordance with the showing in Patent No. 694,480, of March 4, 1902, will result in a retraction of said latch to such an extent as to break it off from the back or main plate to which it is fastened or otherwise impair or destroy its efficiency, and to prevent detrimental retraction of the aforesaid latch is the 15 object of my invention, that consists in a box-fastener of the species shown in the aforesaid patent having the knob or push-lug of its spring-latch provided with a forward shoulder that abuts the adjacent back or main 20 plate subsequent to a clearance of the bolt-lug of said latch from the catch element of the fastener, as is hereinafter more particularly set forth with reference to the accompanying drawings and subsequently claimed.

30 Figure 1 of the drawings represents a fragment of a box provided with my improved fastener for the lid of same, parts of the fastener being broken; Fig. 2, a sectional view on the plane indicated by line 2 2 in the first 35 figure; Fig. 3, a similar view of a portion of the fastener, showing the spring-latch element thereof retracted its full limit; and Fig. 4, a perspective view of the latch detached from the back or main plate of said fastener.

40 Referring by letter to the drawings, A indicates the metal back or main plate of my improved fastener, having a right-angle upper flange b, provided with a longitudinal slot c, and an outer lip d is shown depending 45 from the flange. However, this lip may be omitted, if necessary or desirable, in some instances. Central of plate A the metal of the same is cut out to provide apertures e f, one below the other, and an apertured lateral ear

g is shown struck out from said plate, although it may be made separate from the same and attached thereto.

Riveted or otherwise secured to the rear side of plate A is one end of a spring-metal plate B, provided with a forward beveled bolt-lug h and a forward knob or push-lug i, these lugs being arranged to engage with the aforesaid apertures of said plate.

The above-specified assemblage of parts constitutes the bolt portion of the box-fastener, and the catch portion of said fastener is a strip C, of sheet metal, bent to form a right angle, the vertical or tongue end of which is provided with an aperture j and an apertured outer lateral ear k, this ear being 55 a preferably integral part of said strip.

The fastener as thus far described is the same as the one shown in the patent aforesaid, with the exception that the knob or push-lug i of the spring-latch element of said fastener is provided with a forward shoulder i', that limits retraction of said latch by coming into contact with the back or main plate A of said fastener. As herein shown, the otherwise full-round portion of the knob or push-lug i of the fastener-latch is partly cut away at the top, so as to provide the shoulder i'; but this shoulder may be an annular outer end flange of a full-round lug.

In practice the plate A of the bolt portion 80 of the fastener is fitted on a wall D of a box and secured thereto by nails or screws driven into the same through apertures provided in said plate, the upper longitudinally-slotted flange b of this plate being set flush in the adjacent edge of the box-wall. The flange-lip d, if employed, faces the outside of said wall and a recess provided therein. The box-wall recess is closed at the back by plate A, and the slot c in plate-flange b registers with said 85 recess. The catch portion C of the fastener is secured on the under side of a swinging lid E of the box in position to have its tongue extend through flange-slot c of plate A when the lid is down, and said tongue in its descent 90 strikes the bevel of the bolt-lug h, that normally extends through the aperture e in the plate A of the bolt portion of said fastener.

Hence there is automatic retraction of the spring-plate B to effect a clearance of said tongue by said lug. The lid being full down, the aperture *j* of the fastener-tongue is automatically engaged by bolt-lug *h* of spring-plate B, this plate being then in normal position. The strap or wire of an ordinary metallic seal F may now be engaged with the plate and tongue-ears *g k*, as herein shown.

10 The seal being broken or absent, the knob or push-lug *i* of the spring-plate B is pressed upon to retract said plate and disengage bolt-lug *h* of same from the tongue-aperture of the latch portion of the fastener, so that the box-lid may be swung back on its hinges; but the retraction of said spring plate or latch is limited by the shoulder *i'* of said knob or push-lug. Hence the efficiency of the aforesaid plate or latch cannot be impaired or destroyed

15 by careless, mischievous, or malicious effort exerted on its aforesaid knob or push-lug.

Having thus described my invention, what I claim as new, and desire to secure by Letters Patent, is—

A box-fastener comprising a main plate attachable to a box-wall back of a recess therein, a spring-plate fast at one end to the main plate, a bolt-lug and a shouldered push-lug or knob arranged in connection with the spring-plate to play in main-plate apertures, and a box-lid catch having an apertured vertical tongue portion for engagement with the bolt-lug of said spring-plate. 25

30 In testimony that I claim the foregoing I have hereunto set my hand, at Milwaukee, in the county of Milwaukee and State of Wisconsin, in the presence of two witnesses.

CHARLES M. JOHNSON.
